UNITED STATES PATENT OFFICE.

EUGENE E. AIRES, OF LIMA, OHIO.

CLAMP.

SPECIFICATION forming part of Letters Patent No. 761,282, dated May 31, 1904.

Application filed October 14, 1903. Serial No. 177,037. (No model.)

To all whom it may concern:

Be it known that I, EUGENE E. AIRES, a citizen of the United States, residing at Lima, in the county of Allen and State of Ohio; have 5 invented a new and useful Improvement in Clamps, of which the following is a specification.

My invention relates to eccentric clamps; and the object of the invention is a simple 10 reliable clamp adapted for use in lifting plates of sheet-iron or other similar material, either in a factory, as in a boiler-shop where it is desired to hold the sheet so that it can be operated on by a punching and shearing 15 machine, or the clamp can be used equally as well in building and other construction work where it is necessary to elevate metal plates, platforms, &c.

My invention consists of the novel features 20 of construction and combination of parts hereinafter described, particularly pointed out in the claims, and shown in the accompanying drawings, in which—

Figure 1 is a perspective view of my clamp 25 in use. Fig. 2 is a side elevation of the clamp in use. Fig. 3 is an end view of the clamp, the eccentric lever being shown in a vertical position.

In the drawings, A represents a metal plate 30 to be lifted by my clamp. In constructing the clamp I employ a lever B, perforated adjacent one end, as shown at B', and the opposite end is rounded and slightly enlarged, as shown at B².

The hook member C comprises the straight 35 flat face C', which is adapted to engage the under face of the plate to be lifted. Extending upward from the rear end of the lower horizontal member of the hook on which the face C' is formed are two parallel arms C². These arms are slightly spaced apart and in their lower portions are arranged at a right angle to the face C' and are then bent forward over the horizontal member. The lever 40 B fits between these arms, and the upper forward portion of the arms is pivoted by a suitable bolt to the lever adjacent the rounded head B². A chain D has a link secured in the perforation B' of the lever B.

In use two of these clamps are employed, 50 the chain D being connected at one end to the lever of one clamp and at the opposite end to the lever of the other clamp, and the central part of the chain is engaged by the hook of the hoisting-chain. (Not shown.) 55 When the clamps are placed in the position shown in Fig. 2, it will be obvious that an upward pull on the chain D will tend to lift that end of the lever and that the end B² will be forced downward, bearing on the plate A, 60 which will be held firmly between the end B² and the face C' of the hook.

These clamps will not only hold a plate in a horizontal position, but also at any angle that may be desired. 65

Having fully described my invention, what I desire to secure by Letters Patent and claim as new is—

1. A hook member having parallel, upwardly and forwardly extending arms spaced 70 apart and a straight, flat face formed in advance of the arms, and a lever pivoted between the arms, substantially as described.

2. The combination with a hook member having a flat, smooth face and parallel arms 75 extending over the face, of a lever pivoted adjacent one end between the said arms, and means for lifting the opposite end of the lever.

3. A device of the kind described comprising a member having a straight face, parallel arms extending upwardly from and at right angles to said face and having their upper portions curved over the face, and a lever having a rounded enlarged end fitting between and pivotally connected to the arms. 85

4. A clamp of the kind described comprising a lever perforated adjacent one end and enlarged and rounded at the opposite end, a hook member pivoted to the lever adjacent the enlarged end and having a flat face adapted to lie substantially parallel with the lever, and a chain having one end attached to the perforated end of the lever, substantially as and for the purpose described. 90
